MEANS FOR SHARPENING BITS

James F. McCarthy, Jr., Wallace, Idaho

Application December 7, 1942, Serial No. 468,121

3 Claims. (Cl. 90—21)

The present invention relates to means for sharpening bits and in more particular relates to a device for use on a rock-bit milling machine.

As is well known in the art, such rock-bits ordinarily have a plurality of radial wings for cutting action. The bits are resharpened by inserting a milling tool between the wings and reshaping the wings and the cutting edges. In the sharpening operation, the bit is mounted on a spindle which is swung so that the miller will enter between the wings and perform the sharpening operation.

In the past, the indexing of bits upon a bit holder has either been performed manually or mechanically. The manual operations, while satisfactory to a limited degree, are subject to severe criticism by boards of safety due to the fact that the operator's hand has to be brought into close proximity with high-speed rotary elements. The mechanical indexers heretofore available have been unsatisfactory primarily from the standpoint of their complexity and consequent great cost. In addition, the prior mechanical indexing means taught a construction that prevented their adaptation to equipment of the type to which this invention pertains.

Having in mind these defects of the prior art, it is an object of the present invention to provide an indexing means for rock-bits in sharpening machines.

A further object of the present invention is to provide an indexing means for rock-bit sharpening machines which will accurately index the bit to the proper position.

A further object of the present invention is the provision of an indexing means for rock-bit milling machines, which indexing means will require a minimum of manual attention.

The aforementioned objects of the invention are attained and the defects of the prior art remedied by providing a bit holder of the prior art with an indexing wheel and a locking ratchet; the indexing wheel to be engaged by an adjustable indexing arm, and the locking ratchet to be engaged by a locking pawl. Back and forth operation of the swinging bit holder with a bit placed thereon, to the miller brings the indexing wheel into engagement with the indexing arm to rotate the bit supporting spindle and to bring the bit into proper registry for milling. The locking pawl, or detent, will hold the spindle in position and prevent reversing of the motion of the spindle. As the tool holder is withdrawn from the milling wheel it will ratchet past the indexing arm, which is spring mounted, and be in position

for again returning to the miller with a further indexing movement.

Other objects and advantages which reside in the invention are disclosed in the details of design and construction, which will be more fully disclosed by the following description and the drawings, wherein:

Figure 1 is an end view of a portion of a milling machine showing a milling cutter, a tool holder, and indexing means, with portions of the tool holder in section;

Figure 2 is similar to Figure 1, with the parts shown in elevation;

Figure 3 is a front elevational view of the apparatus shown in Figures 1 and 2;

Figure 4 is a perspective view of an indexing wheel and its supporting spindle;

Figure 5 is a sectional view on the line 5—5 of Figure 1, and shows a locking ratchet;

Figure 6 is a sectional view of an indexing-arm post;

Figures 7 to 12, inclusive, are plan views showing various relative operating positions of the indexing wheel and indexing arm, in relation to each other and to the milling wheel.

Figure 1 shows an end view of the milling wheel 1, which is suitably supported on an appropriate arbor A and bearings in fixed relation to a shaft 2 which carries secured thereto, by appropriate keys, a bit holder head 3. The shaft 2 is suitably journaled for rotation.

Also secured to the shaft is an operating handle 4 by means of which the shaft may be rotated, and the bit holder post swings about the axis of shaft 2 in a manner to bring a bit supported on the holder into contact with the milling wheel 1. The bit holder arm 5 is bearinged in a suitable sleeve 6 supported by a casting 6A attached to the head 3. The bit holder is composed of a boss 7, an indexing wheel 8 and a locking ratchet 9.

The casting 6A is adapted to contain therein a spring-pressed locking detent 10 for engagement with the locking ratchet 9.

An indexing detent 11 is secured in shaft 12, which is carried in a bracket 13 in fixed relation to the arbor carrying the milling wheel 1. A spring 14 is coiled around the indexing arm pin 12 to give it clockwise motion looking down from above as in Figures 7-12. The bracket 13 carries a stop 15 against which the indexing detent 11 is brought to rest by the spring 14. The location of the bracket 13 is adjustable, as is the length of the indexing detent 11, so that some adjustment of the operation of the indexing wheel may be had.

In Figure 1 the under face of the wheel 8 is shown as having an annular recess 17 which receives the upper end extension 18 of the bushing 5 to form a dust seal at this point to protect the bearing surfaces within the bit holder arm. In such sharpening operations as are performed with equipment of this nature a great quantity of fine metallic dust flies about and has an abrasive action upon bearing surfaces between which it may become lodged. As shown in Figure 1, therefore, the wheel 8 serves not only for ratcheting of the pin, but as a deflector and seal for the internal bearing thereunder.

The parts are so mounted with respect to each other and so shaped that when a rock-bit is placed on the boss of the bit holder post and the handle 4 is swung to present the bit to the milling wheel, one of the teeth of the ratchet wheel 8 will have its face contacted by the indexing detent 11 which will cause the indexing wheel to move an angular distance equal to one of its segments as shown in Figures 7 through 10. This movement of the bit holder post will cause the detent 10 to be retracted from one of the locking ratchet indentations 9 and to drop in and engage in the next adjacent one. This detent 10 and the locking ratchet 9 are so shaped that the post 7 can be rotated in one direction only. They also are so shaped and the spring pressure is such that the post is held securely enough in position that the milling of the bit will be true.

After the face between two adjacent wings on the bit has been milled, the handle 4 is withdrawn and the bit and holder are also thereby withdrawn. In withdrawing, the indexing wheel 8 will contact the back side of the indexing detent 11 and be caused to rotate about its axis to leave the stop 15, and to rotate the supporting pin 12 against the action of the spring 14. This motion is detailed in Figure 12, where indexing detent 11 is shown to allow the indexing wheel to pass upon which the arm will then be spring urged against the stop 15 and be held in position for the next forward movement of the bit holder and bit to the milling wheel, when the bit will again be indexed to the next cutting position.

From the above description of the parts of the present device and their operation, it is apparent that applicant has devised an indexing means for a rock-bit holder which needs a minimum of manual operation and skill. All that is necessary is the placing of the bit upon the holding post and the successive operation of the arm 4 to bring the bit into contact with the milling wheel. Motion of the arm causing the back and forth motion of the holder acts to automatically index the holder to the various required positions. The bit is loosely carried on the upper end of the bit holder post and is not secured thereto as by some

positive chucking means. This means that for the first cut the bit may not come into exact registry with the milling wheel, but the uneven pressure of the milling wheel with respect to the two adjacent wing surfaces will align the bit properly with the milling wheel. Further forward and backward movement of the holder will produce accurate indexing of the bit to the further faces to be milled.

10 Having thus described my invention, I claim:

1. In a rock bit sharpening machine of the type employing a rotary sharpening wheel, a rotatable bit holder pin having secured thereto an indexing wheel, a locking ratchet on said pin, means for supporting said pin for swinging movement to and from a sharpening wheel of said machine, an indexing detent pivotally supported, a stop against which said indexing detent rests to immovably hold the same in the path of the 15 forwardly moved indexing wheel, spring means to normally hold said indexing detent against said stop but permitting the indexing detent to swing from the stop upon rearward motion of the indexing wheel, and a detent engageable in the locking ratchet of said bit holder pin to lock the 20 same against counter indexing movement of the pin during rearward movement of the indexing wheel past the indexing detent.

2. In a rock bit sharpening machine of the type employing a rotary sharpening wheel, a bit holder pin having secured thereto a flange immediately below the point at which a bit is supported thereon, teeth on said flange constituting an indexing wheel, means for supporting said pin and including a journal shielded by said flange from 25 cuttings of the sharpening operation, an indexing detent pivotally supported and positioned in the forward path of the indexing wheel, stop means to hold said indexing detent immovably upon forward movement of the indexing wheel whereby the latter is caused to rotate, and spring means to normally hold the indexing detent against its stop but permitting the indexing detent to swing from the stop upon rearward movement of the indexing wheel and pin.

3. In a rock bit sharpening machine of the type employing a rotary sharpening wheel, a bit holder pin having secured thereto an indexing wheel, means for supporting said pin for swinging movement to and from the sharpening wheel of the machine, an indexing detent pivotally supported and positioned in the path of the indexing wheel, a stop against which said indexing detent rests to immovably hold the same upon forward movement of the indexing wheel, and spring means to normally hold the detent against its stop but permitting the detent to swing from the stop upon rearward movement of the wheel.

JAMES F. McCARTHY, JR.
